UNITED STATES PATENT OFFICE

GUSTAV JOHNSON, OF WEST ROXBURY, MASSACHUSETTS, ASSIGNOR TO UNITED-CARE FASTENER CORPORATION, OF CAMBRIDGE, MASSACHUSETTS, A CORPORATION OF MASSACHUSETTS

SLIDE FASTENER

Application filed December 8, 1931. Serial No. 579,695.

My invention aims to provide improvements in sliders for multiple operated fastener installations.

In the drawing which illustrates preferred 5 embodiments of my invention:—

Figure 1 is a plan view of a portion of a multiple operated fastener installation showing my improved slider;

Fig. 2 is a section taken on the line 2—2 10 of Figure 1 showing the slider in locked position;

Fig. 3 is a section similar to that shown in Fig. 2, but showing the slider in unlocked position;

15 Fig. 4 is a section taken on the line 4—4 of Figure 1 to show the construction of the pivot bar and the locking means; and

20 Fig. 5 is a side elevation of my improved slider member formed from sheet metal and with a portion thereof broken away to show the construction.

25 Referring to the drawing which illustrates my invention, I have shown improved slider constructions for use in connection with multiple operated fastening installations. In Figs. 1 through 4 I have shown the slider as being cast from a single piece of metal and in Fig. 5 I have shown the slider as it may be formed from a single piece of sheet metal.

30 My invention relates more particular to the construction of the bar on the slider to which the pull tab is hinged and also to the means for locking the slider in any desired position along the opposed series of fastening elements. Therefore, I shall not attempt 35 further to distinguish between the cast metal slider and the sheet metal slider since both have similar elements for accomplishing the desired results.

40 My improved slider members each have a top plate portion 1, a bottom plate portion 2 and means 3 located between the plate portions adjacent to one end to space the plate portions apart, to connect them together in predetermined relation, and to provide in effect diverging channels for effecting engagement and disengagement of the fastening elements 4 secured to the opposed edges 45 of the stringers 5. Each of the plate members 1 and 2 (Fig. 4) has side flanges 6 ex-

tending toward the side flanges of the other part but being spaced from each other in the usual manner to pass over the stringers while holding the slider in assembled relation as it is moved to and fro along the fastening elements 4. In order to facilitate sliding movement of the slider, I have provided a pull tab 7 which, instead of being attached to a separate bar or being slidably mounted relative to the slider, is preferably attached centrally of the top plate 1, as best illustrated in Figs. 1 and 2. To accomplish the desired attachment of the pull tab 7 I have formed on the top plate 1 of the slider a pivot bar 8 whose longitudinal axis extends transversely across the top plate. This pivot bar is preferably formed by pressing a part of the material of the top plate outwardly and then suitably forming the material to provide a rounded portion in cross-section, as clearly 60 illustrated in Figs. 2 and 3. After the bar 8 has been formed apertures 9 and 10 are provided in the plate portion 1 at each side of the bar. One end of the pull tab is provided with a loop portion 11 which encompasses the 65 curved portion of the bar 8, thereby attaching the pull tab 7 to the slider in pivoted relation thereto.

70 In many multiple operated fastener installations it is desirable to provide means whereby the slider may be located in any desired position along the fastener elements. I have provided a simple and efficient locking means by pressing from the loop portion 11 a projection 12 which is adapted to engage 75 the fastening members 4 either frictionally or between two of them when the pull tab is moved to a predetermined position such, for instance, as shown in Fig. 2.

I have found that there are at least two 80 distinct advantages in pivoting the pull tab member 7 substantially centrally of the top plate. In the first place, the slider may be moved easily in either direction by holding the tab at substantially a right angle to the slider. In the second place, the projection 12 will enter through the aperture 10 in the top plate 1 and engage the fastening elements 4 at a point where they are being separated 85 from each other, thereby permitting the pro- 100

jection 12 actually to engage between the fastening elements rather than to press against them. With this arrangement any lateral stresses exerted upon the stringers tending to separate the fasteners will exert an upward stress against the projection 12, thereby tending to hold the pull tab in locked position, as shown in Fig. 2.

The operation of my device is simple and locking is more or less automatic since in order to move the slider along the fastening elements the pull tab must be moved from a position shown in Fig. 2 to a position shown in Fig. 3, or a more right angled position if desirable, thereby moving the projection 12 from the path of the fastening elements. When the slider is moved to the desired position it is merely necessary to press the pull tab 7 back into the position shown in Fig. 2 and that action swings the projection 12 through the aperture 10 in the plate 1 into engagement with the fastener members 4, as shown in Figs. 1 and 4.

My invention is simple and durable in construction and is reduced to a minimum number of parts the construction and assembly of which is relatively inexpensive.

While I have illustrated and described preferred embodiments of my invention I do not wish to be limited thereby, because the scope of my invention is best defined by the following claims.

I claim:

1. A slider for multiple operated fastener installations having a top portion and a bottom portion spaced apart to permit the passage of opposed series of fastener elements, means located between said portions for guiding the fastener elements of one series into interlocking engagement with the opposed series and for disengaging them as desired, an integral bar formed from one of said portions, the longitudinal axis of said bar extending transversely across the portion from which it is formed, a slide-operating tab having a loop portion surrounding the said bar thereby to constitute with said bar a hinge for said tab, said portion from which said integral bar is formed having an aperture therein adjacent to said bar and a projection extending from said loop portion through the said aperture for engagement with the fastener elements in one position of the tab thereby to lock the slider in a given position with relation to the fastener members.

2. A slider for multiple operated fastener installations having a top portion and a bottom portion spaced apart to permit the passage of opposed series of fastener elements, means located between said portions for guiding the fastener elements of one series into interlocking engagement with the opposed series and for disengaging them as desired, an integral bar formed from one of said portions, the longitudinal axis of said bar ex-

tending transversely across the portion from which it is formed, a slide-operating tab having a loop portion surrounding the said bar thereby to constitute with said bar a hinge for said tab and a projection extending from said loop portion for engagement with the fastener elements in one position of the tab thereby to lock the slider in a given position with relation to the fastener members, and said portion having said bar also having an aperture adjacent to said bar to permit said projection to be entered into and removed from the space between said front and back portions by pivotal movement of said tab.

3. A slide fastener device of the class described having a top plate portion 1, a bottom plate portion 2, means 3 spacing said top and bottom plate portions from each other to permit passage of opposed series of fastener elements through the device, a hinge bar 8 integral with the top plate portion 1 and having its longitudinal axis extending transversely across the top plate portion 1 about midway between the ends of the device, a pull tab member 7 having a loop portion 11 encompassing said bar 8 to provide for pivotal movement of the tab 7 relative to the plate portion 1, an aperture 10 formed in the top plate portion 1 adjacent to said bar 8 and an integral projection 12 formed in said loop portion 11 and adapted to pass through the aperture 10 and intersect the passage between said plate portions 1 and 2 as and for the purposes illustrated and described.

In testimony whereof, I have signed my name to this specification.

GUSTAV JOHNSON.
